J. J. BAKER, SR

WINDOW GUARD

Filed Nov. 5, 1923

UNITED STATES PATENT OFFICE.

JESSE J. BAKER, SR., OF FREEPORT, TEXAS.

WINDOW GUARD.

Application filed November 5, 1923. Serial No. 672,785.

To all whom it may concern:

Be it known that I, JESSE J. BAKER, Sr., a citizen of the United States, residing at Freeport, in the county of Brazoria and State of Texas, have invented certain new and useful Improvements in a Window Guard, of which the following is a specification.

This invention relates to new and useful improvements in a window guard.

One object of the invention is to provide a device of the character described specially designed for the purpose of guarding window openings, so as to permit ventilation, and to exclude rain and intruders.

Another object is to provide a guard of the character described whereby the current of air admitted through the window will be deflected upwardly to protect the occupants of the room from the direct draft, and also to prevent loose papers and the like from being blown off of tables and desks and being scattered about the room.

A further feature of the invention resides in the provision of a window guard which may be easily fitted to any type of window opening, and which is specially adapted for use in connection with the windows of passenger coaches of trains, and office buildings, but which may be advantageously used on the windows of residences as well, or wherever else desired.

A still further feature of the invention resides in the provision of a window guard which may be cheaply constructed and readily installed in any conventional type of window opening, and which may be completely closed when desired.

With the above and other objects in view, this invention has particular relation to certain novel features of construction, operation and arrangement of parts, an example of which is given in this specification and illustrated in the accompanying drawings, wherein:—

Figure 1 shows a plan view of the guard.

Figure 2 shows a fragmentary front view thereof; and,

Figure 3 shows a cross sectional view, thereof taken on the line 3—3 of Figure 1.

In the drawings the numerals 1, 1, designate the side members of the window cas-

ing having the inside grooves 2, 2, in which the sash 3 slides. The numeral 4 designates the bottom ledge of the window casing. 55 These parts above described are of conventional construction.

In the form shown, the guard 10 is arcuate in cross sectional contour and must be made of different lengths to accommodate window openings of varying widths. The ends of this guard has the posts 11, 11, preferably hinged thereto to fit into the sash grooves 2, 2, so as to exclude water at the ends of the guard and its lower edge 65 is turned downwardly to form the flange 13 which is adapted to fit against the outer edge of the ledge 4.

The guard 10 has a cover 14 provided with spaced openings 15 and slidably 70 mounted on this cover are the shutters 16, 16, provided with openings 17 adapted to be moved into and out of registration with the openings 15 through the grips 18 carried by the respective shutters. This type 75 of guard is particularly designed for use on passenger coaches of railway trains or interurban traction railways, but may also be used in residence, office or other windows.

In use the guard is located inside the 80 window on the ledge 4, with the flange 13 resting against the outer edge of said ledge; and the posts 11 resting in the sash grooves 2, 2. The lower sash 3 is then pulled down to rest on the said posts to hold the guard 85 in place. The outer edge of the cover 14 has a flange 14' secured thereto on which the lower edge of the sash may rest to form a water tight joint. As an additional support for the guards, they may be provided 90 with legs, as 19, which rest on the window ledge, and which may be fastened thereto by screws, as 20, if desired.

The concaved side of the guard is disposed to face the incoming air current and 95 deflects said current upwardly, but excludes rain, and when the lower sash is locked in position, prevents the entrance of intruders.

What I claim is:—

A guard for window openings including 100 a transverse inwardly inclined deflector, a downwardly turned engaging flange carried by the lower margin of the deflector, supporting legs for the deflector, an end post

hinged to each end of the deflector and projecting out beyond the corresponding ends of the deflector, a cover for the deflector provided with openings, a flange secured to the outer edge of the cover and projecting outwardly to form a sash support and also adapted to form a water tight joint

with the window sash, a slidably mounted shutter provided with openings adapted to be moved into and out of registration with the cover openings. 10

In testimony whereof I have signed my name to this specification.

JESSE J. BAKER, Sr.
